UNITED STATES PATENT OFFICE.

FRANK J. MANN, OF SCRANTON, PENNSYLVANIA, ASSIGNOR TO SELF-HEATING SOLDERING IRON COMPANY, A CORPORATION OF NEW YORK.

SELF-HEATING SOLDERING-IRON.

No. 900,561.

Specification of Letters Patent.

Patented Oct. 6, 1908.

Application filed December 21, 1907. Serial No. 407,511.

To all whom it may concern:

Be it known that I, FRANK J. MANN, citizen of the United States, residing at Scranton, in the county of Lackawanna and State of Pennsylvania, have invented certain new and useful Improvements in Self-Heating Soldering-Irons, of which the following is a specification.

My invention relates to self-heating soldering irons, and has for its object the construction of an implement bearing its own fuel supply, and having special formation and particular arrangement of parts, whereby it is believed that it is kept sufficiently heated longer with the same amount of gasolene than is the case with other like articles with which I am familiar.

Further, while my invention is thought to be well adapted for general use, the special construction and peculiar disposition of the parts renders it available for numerous jobs of work out of the general line.

The stated objective construction is set forth in the accompanying drawings, of which

Figure 1 represents a side view, principally in vertical section, and Fig. 2 is a fragmentary vertical section taken upon a plane at right angles to the section of Fig. 1 and following the indirect line $x-x-y$.

Like reference letters are employed to point out the same parts throughout the specification and drawings.

The customary block of metal A for melting and applying the solder, has the cavity B, from which extend upwardly a plurality of tubes C, D, secured in the closure E that suitably stops the lower end of the inner or main tube F. The cavity B is thus by way of the tubes C and D in open communication with the interior of the tube F. A fuel space G may be left between the closure or plug E and the valve device H. Any desired form of valve may be used. Its office is to admit gasolene from the reservoir J into tube F, tubes C, D, and cavity B.

In order that my invention may be manipulated without inconvenience from the considerable heat generated, it is usual to provide the handle with a relatively thick outer covering K of leather or the like, which lies immediately around a tube L. The tube L incloses the upper portion of the longer or main tube F, and a protective sleeve M of asbestos is placed between the two tubes.

In Fig. 2 it will be noted that the curved tube N opens into the cavity B of block A, and it will likewise be seen in both Figs. 1 and 2 that the tube N has a nipple O. The bell P surrounds all the tubes with its mouth towards the block A, and directs the flame upon the block A and confines the flame to the vicinity of the tubes.

The tube Q illustrated in both figures is only used when the fuel is coal oil, which is found to work better with the tube Q opening at its upper end into the reservoir J, and having its lower end closed and arranged in the field of the flame.

In order that coal oil may be suitably sprayed through the, ordinarily, very small duct of the nipple O, it seems to be necessary to create a vapor pressure in addition to that required for gasolene which is the fuel usually employed. To aid in promptly setting up the augmented pressure is the function of the extra tube Q extending from the flame area directly into the reservoir, as described.

The operation of my invention may be begun by inverting the whole device and pouring a little gasolene into the bell. This being ignited, the tubes C, D, and N and the block A become heated, and when the gasolene is admitted to those parts by turning valve H, the gasolene is vaporized and a jet of the vapor streams from the nipple O, at once igniting in the presence of air and continuing the heating of the parts while the supply of fuel lasts.

The particular arrangement shown and attainable by reason of the special construction described, renders my invention especially adapted for certain pieces of work where the surfaces to which the solder is to be applied are difficult to reach, as the inside corners of boxes or the bottoms of odd shaped cavities.

Having now described my invention and explained the mode of its operation, what I claim is—

1. In a self-heating soldering iron, the combination with a hollow body portion, of a soldering iron or block provided with a cavity, tubes arranged to afford communication from the cavity of said block with the said hollow body, a valve device arranged to shut off such communication, and a tube projecting exteriorly from the said block and having a nipple whereby a jet of vapor may be directed towards the said block, the said

tube being in communication with the said soldering iron, the supply of fluid being governed by the said valve device, substantially as described.

5. 2. In a self-heating soldering iron, the combination with a hollow body portion adapted to contain fluid fuel, of a soldering iron having a cavity, tubes arranged to afford communication from the cavity of said block with the said hollow portion, a bent tube extending from and returning to the cavity iron and passing between the said tubes first mentioned, the said bent tube having a nipple arranged exteriorly between the said tubes first mentioned and near the iron whereby a jet of vapor may be directed towards the said iron, substantially as described.

3. In a self-heating soldering iron, the combination with a hollow body portion, of a soldering iron or block provided with a cavity, tubes arranged to afford communication from the cavity of said block with the said hollow body, a valve device arranged to shut off such communication, a bell sur- rounding the said tubes, and a tube having a nipple whereby a jet of vapor may be directed towards the said block, the said tube being in communication with the soldering iron, the supply of fluid being governed by the said valve device, substantially as described.

4. In a self-heating soldering iron, the combination with a soldering iron or block pro-

vided with a cavity, of a handle portion provided with a reservoir, tubular connections extending between the said handle portion and the said block whereby the reservoir may be placed in communication with the cavity of the said block, a valve arranged to shut off such communication, a nipple arranged exteriorly near the block and adapted to direct a jet of vapor towards the said block, the said nipple being in communication with the said iron, and the said valve being arranged to shut off the fluid supply, substantially as described.

5. In a self-heating soldering iron, the combination with a soldering iron or block provided with a cavity, of a handle portion provided with a reservoir, tubular connections extending between the said handle portion and the said block whereby the reservoir may be placed in communication with the cavity of said block, a nipple arranged exteriorly near the block and adapted to direct a jet of vapor towards the block, the said nipple being in communication with the said iron, and a valve arranged to shut off the fluid supply, substantially as described.

In testimony whereof I affix my signature in presence of two witnesses.

FRANK J. MANN.
